COMBINED TAPE RECORDER-RADIO WITH BUILT-IN CLOCK OR SIMILAR ARTICLE

Madeleine Aghababian, Fort Lee, N.J., assignor to U.S.
Industries, Inc., New York, N.Y., a corporation of
Delaware

Filed Jan. 10, 1969, Ser. No. 15,294

Term of patent 14 years

Int. Cl. D14—03

U.S. Cl. D56—4

Fig. 1

Fig. 2

Fig. 3

Fig. 4

Fig. 5

Fig. 6

Fig. 7

Fig. 8

FIG. 1 is a front perspective view of a combined tape recorder-radio with built-in clock or similar article showing my new design with the clock in open position; FIG. 2 is a view similar to FIG. 1 with the clock in closed position;

FIG. 3 is a top-plan view thereof;

FIG. 4 is a front elevational view thereof;

FIG. 5 is a left side elevational view thereof;

FIG. 6 is a left side elevational view thereof with the clock in open position;

FIG. 7 is a bottom plan view thereof; and

FIG. 8 is a rear elevational view thereof.

I claim:

The ornamental design for combined tape recorder-radio with built-in clock or similar article, substantially as shown.
